UNITED STATES PATENT OFFICE.

VINTON E. SISSON, OF CHICAGO, ILLINOIS, ASSIGNOR TO WALTER P. MURPHY, OF NEW YORK, N. Y.

REINFORCEMENT FOR THE END WALLS OF RAILWAY BOX-CARS.

1,382,025.

Specification of Letters Patent. Patented June 21, 1921.

Application filed August 22, 1919. Serial No. 319,126.

To all whom it may concern:

Be it known that I, VINTON E. SISSON, a citizen of the United States, residing at Chicago, in the county of Cook and State 5 of Illinois, have invented certain new and useful Improvements in Reinforcements for the End Walls of Railway Box-Cars, of which the following is a specification.

My invention relates to the reinforcement 10 of the end walls of railway box cars of wood construction, and the principal object of the invention is to provide an improved metal reinforcing device for the end of a railway box car which will strengthen the 15 end wall of a car especially against the inertia thrusts of the cargo and rigidify the superstructure of the car, as a whole, against the tendency of the car body to distort or "weave" due to the swinging or swaying 20 movements to which the car is subjected in going over uneven track, rounding curves, stopping, starting, switching, and the like.

The improved end reinforcement may be 25 used for the repair or strengthening of old cars or in the construction of new cars. In the former case the application of the reinforcement involves very little disturbance 30 of the car structure.

The invention consists in the new and improved constructions, arrangements and devices to be hereinafter described and claimed 35 for carrying out the above stated objects and such other incidental objects as will appear from the following description of certain preferred embodiments of the invention 40 illustrated in the drawings.

In the drawings—

Figure 1 is an end elevation of the superstructure of a wooden box car reinforced in 45 accordance with my invention.

Fig. 2 is a view, in perspective, of one of the reinforcing members on the inside of the car.

Fig. 3 is a vertical sectional view on line 45 3—3 of Fig. 1.

Fig. 4 is a fragmentary, vertical sectional view on line 4—4 of Fig. 5, looking in the direction of the arrows.

Fig. 5 is a plan view of the end of the 50 car with the roof boards and purlins removed.

Fig. 6 is a fragmentary view in elevation of the upper portion of the end of a box car illustrating a modified construction.

Fig. 7 is a vertical sectional view on line 55 7—7 of Fig. 6.

Fig. 8 is a view, in perspective, of the end plate reinforcing member in the construction shown in Figs. 6 and 7.

Fig. 9 is a view, similar to Fig. 6, but 60 with certain parts in section, illustrating a modified construction.

Fig. 10 is a sectional view on line 10—10 of Fig. 12.

Fig. 11 is a sectional view on line 11—11 65 of Fig. 9.

Fig. 12 is a plan view with the roof removed of the construction shown in Figs. 9, 10 and 11.

Fig. 13 is a view, in perspective, of the 70 transverse bracing elements on the inside and outside of the car.

Fig. 14 is a fragmentary end elevation illustrating another modification.

Fig. 15 is a detail sectional plan on line 75 15—15 of Fig. 14.

Fig. 16 is a fragmentary plan view of the car with the roof boards removed to illustrate this construction, and

Fig. 17 is a view, in perspective, of one 80 of the transverse bracing members of the construction shown in the last three figures.

Like characters of reference designate like parts in the several figures of the drawings.

The drawings show the end reinforcing 85 structures as applied to wooden cars of common construction. Referring to the parts of the car at one end thereof, 25 indicates the end sill, 26 the end sheathing, 27 the end posts, 28 the diagonal braces, 29 the end 90 plate, 30 the side plates and 31 the end fascia.

The end wall reinforcement in the embodiment of the invention shown in Figs. 1 to 5 inclusive, comprises a pair of upright members, preferably Z-bars, 32, on the outside of the car, and a bracing structure within the car which transmits stresses on the Z-bars to the side walls of the car. The Z-bars are preferably alined with the end posts 27 and 95 are secured thereto by bolts 33 at suitable intervals. The lower ends of the Z-bars may be anchored to the under frame of the car in any suitable manner. For example, I have shown the Z-bars as secured by angle pieces 100 34 to an angle bar 35 fastened to the end sill by bolts 36 and lying upon the dead wood 105 37. The bracing structure on the inside of

the car consists preferably of a transverse member 38 and diagonal braces 39 which extend from the transverse member to the side plates 30. The transverse member consists 5 preferably of an angle bar with its end portions bent as indicated at 40 to aline with the upper ends of the Z-bars. By this arrangement each of the Z-bars may be anchored to the transverse member by a plurality of 10 fastening devices, for example, by three bolts 41 which, it will be understood, extend through the end plate. The transverse member may be fastened to the end plate by intermediately positioned bolts 42 so that a 15 very rigid anchorage is obtained for the upper ends of the Z-bars preventing the bars from either pulling away from the upper end of the car, in case of the shifting of the lading against the end wall, or from changing 20 their angular position under the stresses tending to make the car body weave. The diagonal braces 39 preferably cross each other and are secured together at their crossing by a gusset plate 43. Each diagonal brace is riveted to the inwardly extending flange 44 of the transverse member 38 and 25 to an angular bracket 45 secured to the side plates 30 of the car.

In the modified construction shown in 30 Figs. 6, 7 and 8 the end plate reinforcing member 46 is formed with its outstanding flange 47 along its inner edge instead of along its outer edge. Otherwise the construction is the same as that previously described.

In Figs. 9 to 13 inclusive, the Z-bars 48 are arranged in reverse position, that is, 35 with their outer flanges pointing toward each other, and are connected on the outside 40 of the car by a transverse member 49 consisting preferably of an angle bar with its ends bent downwardly and riveted at 50 to the outstanding webs 51 of the Z-bars. The transverse member 52 on the inside of the 45 end plate is made somewhat longer so that its downturned ends 53 will take the bolts 54 passing through the flanges 55 of the Z-bars. Intermediate bolts 56 passing through the 50 end plate anchor the transverse members 49, 52 one to the other.

In the construction shown in Figs. 14 to 55 17 inclusive, there are also two transverse members, one on the outside of the car and one on the inside of the car, which may be alike but are arranged in reverse position. The transverse member 57 on the outside of the car has its bent ends 58 extending downwardly and secured to the Z-bars by rivets 59. The transverse member 60 on the inside 60 of the car is arranged so that its bent over ends 61 extend upwardly. The inner member is secured to the Z-bars by bolts 62 and to the end plate at intermediate points by bolts 63.

65 In Figs. 14 and 15 I have illustrated an

additional improvement which might be employed in connection with any of the constructions previously described, the object of which is to provide metal braces associated with the Z-bars for taking the thrust of the 70 upper ends of the wooden diagonal braces 28 of the car. These braces consist of angular plates 64 riveted at 65 to the outstanding webs 66 of the Z-bars and adapted to stand in front of the upper ends of the 75 diagonal braces 28 to which they may be secured if desired, by bolts 67. If the braces tend to go out under the pressure of a shift 80 the cargo the plates 64 will tend to hold them in place.

I claim:

1. The combination with the wooden end wall of a railway car, of a metal reinforcing construction for said wall comprising a pair of upright members on the outside of the 85 car wall, and a bracing structure within the car including a transverse element bearing against the inner side of the wall, the ends of which stand at right angles to the main portion thereof and are alined with said 90 upright members respectively, to which said members are secured each with a plurality of fastening devices.

2. The combination with the wooden end 95 wall of a railway car, of a metal reinforcing construction for said wall comprising a pair of upright members on the outside of the wall and a bracing structure within the car including a transverse element bearing against the inner side of the wall, the ends 100 of which are bent to aline with said upright members and to which the latter are secured.

3. The combination with the wooden end wall of a railway car, of a metal reinforcing structure for said wall comprising a pair of 105 upright members on the outside of the wall, and a bracing structure within the car including a transverse element bearing against the inner side of the wall which is angular in cross section and has its ends bent to aline 110 with said upright members, respectively, to which the latter are secured.

4. The combination with the wooden end wall of a railway car, of a metal reinforcing structure for said wall comprising a pair of 115 upright members on the outside of the wall and a bracing structure within the car including a transverse member angular in cross section providing a flange to bear against the inner side of the wall, a flange 120 inwardly projecting therefrom, and diagonal members secured to said projecting flange and to the side walls of the car, the ends of said transverse member disposed at right angles to the main portion thereof and being alined with the upper ends of the upright members, respectively, and the latter being secured thereto each by a plurality of fastening devices.

5. The combination with the wooden end 130

- wall of a railway car, of a metal reinforcing structure for said wall comprising a pair of upright members on the outside of the wall and a bracing structure within the car including a transverse member angular in cross section providing a flange to bear against the inner side of the wall, and a flange inwardly projecting therefrom, and diagonal members secured to said projecting flange and to the side walls of the car, said transverse member being bent at opposite ends to provide portions alined with the upper ends of the upright members respectively, and the latter being secured thereto each by a plurality of fastening devices. 10
6. The combination with the wooden end wall of a railway box car, of a pair of Z-bars substantially vertically arranged on the outside of the end wall and a bracing structure within the car comprising a transverse member angular in cross section, the ends of which are bent to lie parallel with the upper ends of the Z-bars and the Z-bars secured thereto each by a plurality of fastening devices which extend through the wall. 20
7. The combination with the wooden end wall of a railway box car, of a pair of Z-bars substantially vertically arranged on the outside of the end wall and a bracing structure within the car comprising a transverse member angular in cross section, the ends of which are bent to lie parallel with the upper ends of the Z-bars and the Z-bars secured thereto each by a plurality of fastening devices which extend through the wall, and diagonal braces which are fastened to the transverse member and extend to and are anchored to the side walls of the car. 30
8. The combination with the wooden end wall of a railway box car, of a pair of Z-bars substantially vertically arranged on the outside of the end wall and a bracing structure within the car comprising a transverse member angular in cross section, the ends of which are bent to lie parallel with the upper ends of the Z-bars and the Z-bars secured thereto each by a plurality of fastening devices which extend through the wall, brackets on the side walls of the car, and diagonal braces which extend from the transverse member to the brackets. 40
9. The combination with the wooden end wall of a railway box car comprising end posts, end sill, end plate and sheathing, of a pair of Z-bars on the outside of the wall alined with said end posts, means for anchoring the lower ends of the Z-bars to the end sill, a vertically disposed arched transverse member angular in cross section on the inside of the wall to which the upper ends of the Z-bars are connected, and diagonal braces from said arched member to the side walls of the car. 50
10. The combination with the wooden end wall of a railway box car, of a metal reinforcing construction for said wall comprising a pair of upright members on the outside of the car wall, a transverse member for connecting the upper ends of the upright members, the ends of which stand at right angles to the middle portion thereof and are alined with said upright members, and means for securing each upright member to the alining portions of said transverse member. 60
11. The combination with the wooden end wall of a railway box car, of a metal reinforcing construction for said wall comprising a pair of upright members on the outside of the car wall, a transverse member on the outside of the car wall, the ends of which are bent into alinement with and are secured to said upright members. 70
12. The combination with the wooden end wall of a railway box car, of a metal reinforcing construction for said wall comprising a pair of upright members on the outside of the car wall, a transverse member on the outside of the car wall which is angular in cross section and the ends of which are bent into alinement with and are secured to said upright members. 80
13. The combination with the wooden end wall of a railway box car, of a pair of upright members on the outside of the car, a transverse member on the outside of the car having its ends bent into alinement with the upright members and connected thereto, and a transverse member within the car to which the aforesaid members are secured by fastening devices passing through the wall. 90
14. The combination with the wooden end wall of a railway box car, of a pair of upright members on the outside of the car, a transverse member on the outside of the car having its ends bent into alinement with the upright members and connected thereto, and a transverse member within the car having its ends bent into alinement with said upright members to which the latter are secured by fastening devices passing through said wall. 100
15. The combination with the wooden end wall of a railway box car, of a pair of upright members on the outside of the car, a transverse member angular in cross section on the outside of the car having its ends bent into alinement with the upright members and connected thereto, and a transverse member angular in cross section within the car having its ends bent into alinement with said upright members to which the latter are secured by fastening devices passing through said wall. 110
16. The combination with the wooden end wall of a railway box car, of a pair of upright members on the outside of the car, a transverse member angular in cross section on the outside of the car having its ends bent into alinement with the upright members and connected thereto, and a transverse member angular in cross section within the car having its ends bent into alinement with said upright members to which the latter are secured by fastening devices passing through said wall. 120
17. The combination with the wooden end wall of a railway box car, of a pair of upright members on the outside of the car, a transverse member angular in cross section within the car having its ends bent into alinement with the upright members and connected thereto, and a transverse member angular in cross section on the outside of the car having its ends bent into alinement with the upright members and connected thereto. 130

on the outside of the car having its ends bent into alinement with the upright members and connected thereto, a transverse member angular in cross section within the 5 car having its ends bent into alinement with said upright members to which the latter are secured by fastening devices passing through said wall, and diagonal bracing members which extend from said last named 10 transverse member to the side walls of the car.

17. The combination with the wooden end wall of a railway box car comprising wooden end posts and diagonal braces, of a 15 metal reinforcing construction for said wall comprising a pair of upright members on the outside of the wall alined in parallelism with said end posts and members secured to and extending laterally from said upright 20 members in position to take the thrust of the diagonal braces when the end wall of the car is under stress of a shifting lading.

18. The combination with the wooden end

wall of a railway box car comprising wooden end posts and diagonal braces, of a pair of 25 Z-bars on the outside of the car alined with said posts, and member angular in cross section secured to said Z-bars in position to stand in front of the upper ends of said diagonal braces for the purpose described. 30

19. The combination with the wooden end wall of a railway box car, of a metal reinforcing construction for said wall comprising a pair of upright members on the outside of the car wall and transverse members, one on the inside of the car and one on the outside thereof adjacent the upper ends of said upright members, the ends of said transverse members being disposed at right angles to the middle portions thereof 40 and in alinement with said upright members, and means for securing each upright member to the alining portions of said transverse members.

VINTON E. SISSON.

It is hereby certified that in Letters Patent No. 1,382,025, granted June 21, 1921, upon the application of Vinton E. Sisson, of Chicago, Illinois, for an improvement in "Reinforcements for the End Walls of Railway Box-Cars," an error appears in the printed specification requiring correction as follows: Page 4, line 27, claim 18, for the word "member" read *members*; and that the said Letters Patent should be read with this correction therein that the same may conform to the record of the case in the Patent Office.

Signed and sealed this 16th day of August, A. D., 1921.

[SEAL.]

WM. A. KINNAN,

Acting Commissioner of Patents.

Cl. 105—411.
